UNITED STATES PATENT OFFICE

142,295

DESIGN FOR A VERTICAL SHAFT FOR ANDIRONS

Ernest O. Crocker, Washington, D. C.

Application March 24, 1945, Serial No. 118,664

Term of patent 3½ years

(Cl. D81—6)

To all whom it may concern:

Be it known that I, Ernest O. Crocker, a citizen of the United States and a resident of Washington, District of Columbia, have invented a new, original, and ornamental Design for a Vertical Shaft for Andirons, of which the following is a specification, reference being had to the accompanying drawing, forming a part thereof.

Figure 1 is a front elevational view of a ver-

tical shaft for andirons showing my new design.

Figure 2 is a side view of the same.

The dominant features of the design reside in the portions shown in full lines.

I claim:

The ornamental design for a vertical shaft for andirons, as shown and described.

ERNEST O. CROCKER.
